PIPE CUTTER

John R. Jobe, Houston, Tex.

Application March 24, 1945, Serial No. 584,621

8 Claims. (Cl. 164—0.4)

This invention relates to a pipe cutter.

An object of the invention is to provide a cutter of the character described specially designed to be lowered into a pipe stuck in a well bore and to sever the same, or to so weaken the pipe that an upper section of the pipe may be removed from the well.

The invention also embodies means whereby the tool may be located in the pipe at the point where it is desired to make the cut.

It is a further object of the invention to provide a pipe cutter which may be lowered into pipe, and operated, by a wire line.

With the above and other objects in view this invention has particular relation to certain novel features of construction, operation and arrangement of parts an example of which is given in this specification and illustrated in the accompanying drawings, wherein:

Figure 1 shows a vertical, sectional view of the cutter in a pipe and in inactive position.

Figure 2 shows a vertical, sectional view thereof, in active position.

Figure 3 shows a sectional view taken on the line 3—3 of Figure 1.

Figure 4 shows a sectional view taken on the line 4—4 of Figure 2.

Figure 5 shows a sectional view taken on the line 5—5 of Figure 2.

Figure 6 shows a fragmentary side view of the cutter.

Figure 7 shows a side elevation, partly in section, of another embodiment of the invention.

Figure 8 shows a sectional view taken on the line 8—8 of Figure 7, and

Figure 9 shows a cross sectional view taken on the line 9—9 of Figure 1.

Referring now more particularly to the drawings, wherein like numerals of reference designate the same parts in each of the figures the numeral 1 designates a downwardly tapering mandrel to the upper end of which the jar 2 is connected. This jar is formed of links slackly connected together. At its upper end the jar is formed with a threaded pin 3 for the connection of a rope socket, as 4, thereto and to which a wire operating line 5 may be connected.

Threaded onto the lower end of the mandrel there is guide 6 whose lower end is pointed. Above the guide the mandrel is provided with a vertically elongated, transverse, slot 7.

The guide has a deep, axial, socket 8 extending down from its upper end and also has a side slot 9. In the socket 9 there is a carrier 10 and a finger 11 is pivoted at its lower end to said carrier and its upper end is adapted to work through the slot 9.

There is a cross rod 12 through the slot 7 and a frangible pin 13 is fitted through the upper end of the carrier 10 and the rod 12 to pin them to-

gether. The upper end of the carrier is reduced forming an external, upwardly facing shoulder 14 and the guide 6 has an inside, downwardly facing shoulder 15 with which the shoulder 14 is adapted to engage.

Around the lower end of the mandrel there is a support 16 through which the ends of the rod 12 extend so that the pin 13 and carrier 10 will hold the support 16 in its lower position, on the 10 mandrel, while going into the well.

There are the knife arms 17 whose lower ends are pivotally connected to the support 16 and upstand therefrom, as shown more accurately in Figure 6. The upper ends of these arms carry 15 the transverse, outwardly directed, blades, or knives, 18 having the outwardly curved cutting edges 19 having the same curvature as the pipe 20 to be cut as shown in Figure 3.

In use the tool may be assembled as shown in Figure 1 and lowered into the pipe 20. The support 16 will be held in its lower position on the mandrel by the carrier 10, which is connected thereto by pin 13 and rod 12, and the arms 17 and blades 18 will be retracted. The outer end of the finger 11 will ride against the inside of the pipe 20 as the tool is lowered.

When the level has been reached at which it is desired to make a cut the tool may be pulled upwardly and the free end of the finger 11 will engage in the coupling 21 of the pipe and will stop the further upward movement of the carrier 10 and upon further upward movement of the tool the pin 13 will be sheared and the carrier 10 will drop down into the socket 8 thus retracting the finger 11. The tool may then be suddenly dropped and the inertia of the support 16 and arms and blades thereon will allow the tapering portion of the mandrel to move down between the arms and expand them and force the blades 40 into contact with pipe 20 to arrest the further downward movement of the tool. The jaws may then be successively elevated and dropped to gradually force the mandrel further downwardly, thus forcing the blades outwardly through the pipe as shown in Figure 2.

The mandrel may then be pulled upwardly and the arms will be released and when the upper end of the guide 6 engages the support 16 the arms will be forced upwardly and the downwardly sloping upper sides of the blades will cause them to disengage the pipe and the tool may be removed from the well.

As shown in Figure 2 the blades, when expanded, will be spaced a distance apart, circumferentially, and will not, therefore, completely sever the pipe but will so weaken it that it can be pulled in two. When the tool is removed from the pipe a pipe puller, of conventional construction, can be lowered into the well and engaged 55 with the upper end thereof and the pipe pulled in 60

two and the severed section removed. The cutting and pulling operation can be repeated as often as necessary until the recoverable portion of the stuck pipe has been removed from the well.

In the embodiment shown in Figure 7 the rope socket, jaws, the tapering mandrel, and the blade arms and blades are substantially the same as shown in Figure 1. However the blade arm support 22 is cylindrical in shape and has an elongated vertical slot 23 extending entirely therethrough, transversely and a cross-yoke 24 extends through the lower end of the mandrel and is pinned therein with its ends extended into said slot on each side. The support 22 also has an axial bore 25 extending from end to end thereof.

Before lowering this embodiment of the tool into the stuck pipe a tool support is lowered into the pipe and set at the desired location and on which the tool may land. In the present illustration this tool support consists of a body 26 having the downwardly converging side faces 27, 27 on which the wedge shaped slips 28, 28, are dovetailed and mounted to slide. Their downward movement is limited by the upwardly facing shoulders 29, 29 beneath. The upper end of the body 26 is provided with an eye 30. A rope may be looped through the eye 30 and the tool support lowered to the desired points in the stuck pipe. The jaws 28 will be in their lower inner position. The tool support may then be suddenly dropped and the inertia of the jaws will cause them to be expanded. They are externally toothed and when expanded will engage the pipe 20 and anchor the tool support in place. The rope used in locating the tool support may then be withdrawn.

The cutting tool may then be lowered until it lands on the tool support and the mandrel forced down by successive strokes of the jaws 2 until the blades are forced through the pipe 20 to partly sever it. Thereupon the tool may be elevated to release the blades from the pipe, as before, and the tool partly turned and again lowered onto the tool support and another cut made to sever the pipe between the preceding cuts and a section of pipe thus completely severed and which may be pulled out by a pipe puller, after the cutter has been removed.

What I claim is:

1. A pipe cutter comprising, a mandrel, a support releasably secured to said mandrel and forming an inertia body, arms upstanding from said support, blades on said arms, means for releasing the mandrel from the support to allow the independent downward movement of the mandrel relative to the inertia body, said mandrel being shaped to expand the arms and blades to force the blades into cutting relation with the pipe and impact means at the upper end of the mandrel whereby the mandrel may be driven downwardly and the blades forced through the pipe.

2. A pipe cutter comprising, a cutter body which has a downwardly tapering portion, a blade support slidable on the body, outwardly movable blades mounted on the blade support and arranged to be expanded by said tapering portion upon downward movement of the body, said support being adapted to hold the blades against downward movement, by inertia, as the body moves downwardly.

3. A pipe cutter comprising, a cutter body which includes a mandrel having an expander, a blade support movable, by inertia, relative to the body, blades on the support around the body arranged to be expanded by said expander upon such movement.

4. A pipe cutter shaped to be lowered into a well pipe and comprising, a cutter body which includes a mandrel having a blade expander, a blade support slidable on the body, supporting arms upstanding from said support around the expander, outwardly directed blades on said arms, said support being adapted to be held, by inertia, as the mandrel and expander are moved to expand the blades.

5. A pipe cutter comprising, a cutter body which includes a mandrel having a blade expander, a blade support on the body, means including a frangible element for holding said support against substantial movement on the body, blades mounted on the support, means engageable with the pipe to be cut and effective to retain said holding means, upon upward movement of the body in the pipe, whereby said frangible element will be broken to allow the body to move independent of the blade support and blades, said expander being arranged to expand the blades to penetrate the pipe upon subsequent downward movement of the expander.

6. A pipe cutter shaped to be lowered into a pipe in a well and comprising, a cutter body which includes a mandrel having a blade expander, a blade support movable by inertia relative to the body, upstanding, outwardly movable arms on the support, outwardly directed blades on the arms, said expander being arranged to move the arms and blades outwardly upon downward movement of the body relative to the support.

7. A pipe cutter shaped to be lowered into a pipe in a well and comprising, a cutter body which includes a mandrel having a blade expander, a blade support associated with the body, outwardly movable arms upstanding from the support, outwardly directed blades on the arms, means for retaining the support against substantial movement, relative to the body, while the tool is being lowered into the pipe, means for releasing said retaining means, upon subsequent upward movement of the tool in the pipe, said support being adapted to be held by inertia and said expander being arranged to expand the arms and blades upon subsequent downward movement of the body.

8. A pipe cutter shaped to be lowered into a well pipe and comprising, a cutter body which includes a mandrel having a blade expander, a blade support slidable on the body, supporting arms upstanding from said support around the expander, outwardly directed blades on said arms arranged to be initially moved into contact with the pipe, upon initial downward movement of the expander to support the tool in the pipe, and impact means, under the control of an operator for driving the body and expander further downwardly between the arms to expand the arms and blades to cause the blades to penetrate into the pipe.
